UNITED STATES PATENT OFFICE.

JOHN LAIDLAW, OF GLASGOW, SCOTLAND, AND CHARLES A. MATTHEY, OF
READING, ENGLAND.

CENTRIFUGAL MACHINE.

SPECIFICATION forming part of Letters Patent No. 592,147, dated October 19, 1897.

Application filed March 10, 1896. Serial No. 582,599. (No model.)

To all whom it may concern:

Be it known that we, JOHN LAIDLAW, engineer, of the city of Glasgow, Scotland, and CHARLES ALPHONSO MATTHEY, engineer, of 5 Reading, Berkshire, England, have invented certain Improvements in Self-Balancing Centrifugal Machines, of which the following is a specification.

This invention relates to that class of centrifugal machines known as "Weston's centrifugal machines or hydro-extractors," in which the basket is suspended from above in such a manner that it is more or less self-balancing, while permitted to have some freedom of oscillation.

In carrying out our invention we rotate the basket by means of a turbine or motor attached directly to the spindle of the basket. Water or any elastic fluid, such as steam or 20 non-elastic fluid, may be employed under suitable pressure to actuate the turbine or motor. When using water or other non-elastic fluid to drive the turbine or motor, we provide flanges, baffles, or guards, so as to prevent the fluid 25 from getting into the basket or oil-chamber or escaping by any other way except by the opening or outlet provided for the purpose.

In the drawings, Figure 1 is a vertical section, and Fig. 2 a horizontal section on the line indicated, showing the turbine applied to the suspended machine as at present constructed. Fig. 3 is a vertical section, and Fig. 4 a plan, showing the turbine applied to the machine with improved means of suspension. Fig. 5 is a vertical section, and Fig. 6 is a horizontal section on the line indicated, 35 of a modification. Fig. 7 is a partial elevation and a partial section of another modification.

40 A A is the framework of the machine.

B B is the shaft carrying the basket and supported by the usual elastic suspension C C. We attach to the shaft a turbine or other motor D D for driving the shaft and basket. The framework connecting the buckets E E with the shaft B is provided with 45 flanges F F, and the fixed framework has also flanges G G attached, which overlap the

flanges F F, as shown in Fig. 1. These flanges are provided to prevent the water or other 50 fluid getting into the basket or oil-chambers or escaping by any other way except the opening H, provided for the purpose.

In Fig. 3 our improved means for the suspension of the shaft carrying the basket is 55 illustrated. The shaft B terminates in a portion of a sphere b, and is supported in a corresponding socket c, which is carried on the framework A in a receptacle I. There is an annular space between the socket and the walls 60 of the receptacle, in which there is placed a spring or springs d, made of metal or other elastic substance. The socket has thus some freedom of motion. The above-described suspension renders the basket very completely 65 self-balancing.

Under certain conditions of work the springs d, surrounding the socket c, may be dispensed with.

Fig. 5 is a vertical section, and Fig. 6 a 70 horizontal section, of a modification of our invention, in which the turbine-case is free to oscillate with the shaft and basket. In this case the turbine-case is supported on gimbals, so as to be free to move with the spindle, or it may 75 be supported by means of a ball-and-socket arrangement, as shown in Fig. 7. In this case the supply-pipe must be made flexible.

We claim—

The combination, with the shaft of a self-balancing suspended centrifugal machine; of a framework provided with an inwardly-projecting flange, and the motor provided with an outwardly-projecting flange overlapping the flange of the framework to prevent the 85 escape of the fluid except through the opening provided for the purpose; substantially as described.

In testimony whereof we have signed our names to this specification in the presence of 90 two witnesses.

JOHN LAIDLAW.
C. A. MATTHEY.

Witnesses:

JOHN LIDDLE,
ARTHUR HARTLEY YUILE.
